UNITED STATES PATENT OFFICE.

GEORGE W. WRIGHT, OF CARTERVILLE, MISSOURI.

PLOW.

SPECIFICATION forming part of Letters Patent No. 339,610, dated April 6, 1886.

Application filed January 4, 1886. Serial No. 187,550. (No model.)

To all whom it may concern:

Be it known that I, GEORGE W. WRIGHT, of Carterville, in the county of Jasper and State of Missouri, have invented a new and useful Improvement in Plows, of which the following is a specification, reference being had to the annexed drawings, forming a part thereof, in which—

Figure 1 is a plan view. Fig. 2 is a side elevation. Fig. 3 is an inverted plan view of the landside and mold-board. Fig. 4 is an inside view of the mold-board.

Similar letters of reference indicate corresponding parts in the different figures of the drawings.

The object of my invention is to facilitate the turning of adhesive soil, to reduce the power required to draw the plow forward, and to avoid the necessity of maintaining a high polish on the face of the plowshare, mold-board, and landside.

My invention consists in the combination, with the mold-board and landside of a plow, of means for maintaining them in a heated condition.

In my drawings I have shown means for carrying out my invention, consisting in the application to the back of the mold-board and landside of the plow of a steam-jacket supplied with steam by a boiler carried on the frame of the plow, the steam-jackets of the mold-board and landside being provided with means for removing the water of condensation. The beam A of the plow is formed of two parallel bars of iron separated at the forward end by a plate, a, carrying the bearing b of the axle c of the caster-wheel d, the caster-wheel d being journaled on the end of the crank-axle c, pivoted to the bearing b. The axle c is provided with a clevis, e, to which horses are attached in the usual way. The rear ends of the bars forming the beam A are secured to opposite sides of an arm, B, which extends downward, and is bent outward laterally at right angles to receive the wheel C, which rolls on the bottom of the furrow.

To an arm, D, secured between the bars of the beam A, near the rear end thereof, and extending downward and forward, is pivoted the landside E of the plow F, and the standard G of the plow extends upward between

the bars of the beam A. An annular frame, H, is secured to the side of the beam A at a point opposite the plow F, and is stayed by a brace, I, which is secured to the outer side of the annular frame H, and also to the forward end of the beam A. The annular frame H is also further supported by an arm, J, (shown in dotted lines in Fig. 1,) which projects from the side of the beam A at right angles, and is bent forward at right angles at its outer end and attached to the annular frame H.

To the arm J are secured the boxes f of the rear axle, K, which projects beyond the outer box and beyond the annular frame H, and carries at its outer end a wheel, L. The end of the axle K nearest the beam A supports a lever, M, placed loosely on the axle, and provided with a bolt, g, which engages a curved notched bar, h, secured to the inner side of the beam A, the bolt g serving to hold the lever M in any desired position.

To the boss of the lever M is secured a toothed sector, i, and to the end of the axle K, outside of the lever M, is secured a lever, N, provided with a bolt, j, which engages the toothed sector i, and holds the axle K in any desired position relative to the lever M. The lever M is connected by a rod, O, with the upper end of the standard G of the plow F by pivotal connections, so that by moving the lever M the share of the plow may be elevated or depressed. When the bolt j of the lever N is in engagement with the toothed sector i, the movement of the lever M simultaneously tilts the plow and turns the axle K, so that the standard of the plow is maintained in an approximately vertical plane. A steam-boiler, P, of any approved construction, is supported by the annular frame H, and the annular frame H is provided with an arm, l, which carries a caster-wheel, m, having on its pintle a spiral spring, n, placed between the arm l and the shoulder formed at the lower end of the pintle, to provide a yielding bearing for the landside of the boiler, to assist in carrying the weight of the boiler when the plow is to be raised or lowered. The mold-board Q is provided with a steam jacket or back, R, and the landside S is provided with a steam jacket or back, T. The lower part of the steam-jacket R of the mold-board and the rear end of the jacket T of the landside are

connected with each other and with the valve *o* by the pipe *p*, which forms a way of escape for the water of condensation from the jackets *R*, *T*, and also acts as a brace between the landside and mold-board. The jackets *R* *T* communicate with each other at the lower part of the plow, and the top of the jacket *R* is connected by a flexible pipe, *q*, and through the valve *r* with the steam-room of the boiler, and the bottom of the jacket *R* of the mold-board is connected by the pipe *s*, flexible pipe *t*, and pipe *u* with the top of the water-reservoir *U*, the pipe *u* being provided with a valve, *v*. The water-reservoir communicates with the steam-room of the boiler through the valve *w*, and with the water-space of the boiler through the valve *x*, and the top of the water-reservoir *U* is provided with an air-cock, *y*. Steam is generated in the boiler *P*, and is permitted to pass to the jackets of the mold-board and landside through the valve *r* and pipe *q*, and the water of condensation is allowed to escape from jackets of the landside and mold-board through the pipe *p* and valve *o*, or it may be returned to the boiler by opening the air-cock *y* in the top of the water-reservoir *U* and opening the valve *v* in the pipe *u*, the valves *w* *x* being closed, when the steam-pressure in the jackets will force the water contained in the lower portion thereof through the pipes *s* *t* *u* to the water-reservoir *U*. The feeding of the boiler *P* is effected by closing the air-cock *y* and opening the valves *w* *x* more or less, thus equalizing the pressure in the water-reservoir, and permitting the water to flow by its own gravity from the reservoir through the valve *x* into the water-space of the boiler. Should it be found undesirable to maintain the boiler-pressure in the jackets *R* *T* during the time of supplying the boiler with water, the valve *v* in the pipe *u* may be closed.

I have described a means of heating the mold-board and landside of a plow by the use of steam; but the same effects may be produced by heating it in any other way; but I prefer steam as being the most convenient and not liable to injure the temper of the mold-board or landside.

By heating the mold-board and landside of the plow in the manner described a thin stratum of steam is formed of the moisture of the soil on the surface of the mold-board, which separates the soil from the mold-board and landside, causing it to slide over the plow and to turn with greatly-diminished friction, so that less power is required to draw the plow forward, and the polish of the mold-board and landside will require less care and attention.

When the soil contains so little moisture as to render it impossible to generate enough

steam on the face of the mold-board to cause the soil to slide freely over the mold-board, I provide in the lower edge of the mold-board or landside, or both, one or more small apertures, *a'*, communicating with the steam-jacket and furnishing a small amount of steam to the rubbing faces of the plow.

I am aware that the mold-boards of plows have been heated to cause the soil to slide over them. Therefore I do not broadly claim the heating of mold-boards.

Having thus described my invention, what I claim as new, and desire to secure by Letters Patent, is—

1. In a plow, a mold-board provided with a steam-jacket upon the back thereof and means for supplying steam to the jacket and removing the water of condensation therefrom, substantially as herein specified. 75

2. The combination, with the mold-board or landside of a plow having apertures *a'*, of a steam-jacket placed on the back of the mold-board or landside for supplying a stratum of steam to the face thereof through the holes *a'*, 80 substantially as described.

3. In a plow, a mold-board and landside, each provided with a steam-jacket on the back thereof, and means for supplying steam to the jackets and removing the water of condensation therefrom, substantially as herein specified. 90

4. In a plow, the combination of the mold-board *Q*, provided with the steam-jacket *R* on the back thereof, and the landside *S*, provided with the steam-jacket *T* on the back thereof, the pipe *p*, connecting the steam-jackets *R* *T* and serving as a brace between the landside and mold-board of the plow, substantially as herein specified. 95

5. In a plow, the combination, with the mold-board *Q*, provided with the steam-jacket *R*, and the landside *S*, provided with the steam-jacket *T*, of the boiler *P*, carried by the frame of the plow, and pipe-connections between the steam-room of the boiler and the steam-jackets, substantially as herein shown and described. 105

6. In a plow, the combination, with the mold-board *Q*, provided with the jacket *R*, and the landside *S*, provided with the jacket *T*, of the pipe *p*, the boiler *P*, the water-reservoir *U*, provided with the air-cock *y*, the valves *w* *x*, and the flexible pipe-connections connecting the boiler and the water-reservoir *U* with the jackets *R* *T*, substantially as herein shown and described. 115
